UNITED STATES PATENT OFFICE.

HORACE G. MCLEAN, OF MCPHERSON, KANSAS.

SNAP-HOOK.

SPECIFICATION forming part of Letters Patent No. 397,136, dated February 5, 1889.

Application filed June 21, 1888. Serial No. 277,803. (No model.)

To all whom it may concern:

Be it known that I, HORACE G. MCLEAN, of 5
McPherson, McPherson county, Kansas, have
invented an Improvement in Snap-Hooks, of
which the following is a full, clear, and exact
description, reference being had to the accom-
panying drawings, forming a part hereof.

My invention relates to the class of snap-
hooks having a movable jaw or lever pivoted
10 to a main portion, having an eye at one end
and a jaw at the other; and it consists in the
peculiar construction, combination, and ar-
rangement of parts, hereinafter set forth, and
pointed out in the claim.

15 In the drawings, which illustrate the manner
of carrying out my invention, Figure 1 is
an edge view of the device in a closed position.
Fig. 2 is a perspective view of same.

The object of my invention is to make a
20 snap-hook which will be cheap and simple in
manufacture and possess great strength and
durability.

A represents the eye or that part to which
the strap or rein is connected, and B the shank
25 or extension leading from the eye and termin-
ating in a curve or jaw, C.

D indicates an arm or lever, also provided
with a curve or jaw, C, at one end, such jaw
being the reverse of but corresponding to the
30 jaw upon shank B, so that when the lever D
is in its normal position upon one side of said
shank the two jaws will rest upon each other,
as shown. The opposite end of lever D is pro-
vided with an elevated portion, E, which is lo-
35 cated at an angle to the main body of said le-
ver. Said lever D is provided with one or
more hinge-lugs, a, upon its under side, and
it is pivoted or fulcrumed to one face of shank
B by means of pin or rivet b, passing through
40 lugs a, so that when the end E is depressed

the jaw carried by said lever will open in a
plane at right angles to the flat side of the
jaw carried by shank B, as indicated by dot-
ted lines in Fig. 1. Beneath the elevated end
E, and between it and shank B, I locate a 45
small spiral spring, e, with its opposite ends
in suitable sockets formed in said parts.

By depressing elevated end E of lever D the
jaw C carried thereby will be opened, as indi-
cated, while at the same time such movement 50
of the lever will compress spring e. The jaws
C C are provided with oppositely-located lugs
d d, which are provided with oppositely-in-
clined surfaces upon their inner sides, so that
said jaws will be forced apart by a ring or 55
other device entering between said lugs.

In opening the lugs d d describe a line at
right angles to the flat sides of the jaws C C.

Having thus described my invention, what I
claim is—

60 In a snap-hook, the shank or body B, hav-
ing eye A at one end and an open hook at the
opposite end, lever D, provided with a hook
at one end and with an outwardly-turned ele-
vated portion, E, at the opposite end, and 65
which has hinge lug or lugs a formed upon its
inner side, said lever being pivoted to one
side of shank B, so that the hook will open in
a plane at right angles to the flat side of the
jaw carried by the shank, pin b, which con- 70
nects lug or lugs a to said shank, and spring
e, located between elevated portion E and the
shank of the hook, substantially as described.

In testimony whereof I affix my signature in
presence of two witnesses.

HORACE G. MCLEAN.
